United States Patent Office.

SAMUEL McCARTNEY, OF ST. LOUIS, MISSOURI.

Design No. 2,667 dated June 4, 1867.

DESIGN FOR A TRADE-MARK.

The Schedule referred to in these Letters Patent and making part of the same.

TO ALL WHOM IT MAY CONCERN:

Be it known that I, SAMUEL McCARTNEY, of the city of St. Louis, in the county of St. Louis, and State of Missouri, have originated and designed a new Design for a Trade-Mark, of which the following is a full, clear, and exact description, reference being had to the accompanying drawing, making part of this specification.

My design consists of a foul anchor, in combination with the letters S, Mc., and C, and the ornaments B and B', arranged substantially as shown in the drawing annexed hereto. The stock of the anchor terminates in a knob at either extremity, and has one end bent in the manner shown in the drawing.

This design is intended to be used as a brand, and the ring, stock, shank, and arm of the anchor, and also the initials S, Mc., and C, have such breaks or openings in them as may be necessary to give the requisite strength to the plate by which the impression is made.

What I claim as my invention, and desire to secure by Letters Patent, is—

The design for a trade-mark as herein set forth and shown.

SAMUEL McCARTNEY.
